Victor J. Evans BY ATTORNEY

UNITED STATES PATENT OFFICE.

HENRY P. DAVIS, OF NEW YORK, N. Y.

WINDOW-FRAME.

1,313,675.

Specification of Letters Patent. Patented Aug. 19, 1919.

Application filed March 15, 1918. Serial No. 222,706.

To all whom it may concern:

Be it known that I, HENRY P. DAVIS, a subject of the King of Great Britain, residing at New York city, in the county of New York and State of New York, have invented new and useful Improvements in Window-Frames, of which the following is a specification.

This invention relates to window frames and particularly refers to frames for clamping the glass or other transparent element in position in the window opening of vehicle tops.

The primary object of the invention is the provision of a window frame which serves as a quick and effective means of positioning the glass in the opening in the top, said frame also presenting a neat appearance.

Another object of the invention is the provision of a frame of the character described which comprises a pair of separable, identically formed clamping sections which are provided with means whereby the same can be snapped together to grip the edge of the cloth and at the same time clamp the glass in position.

A further object of the invention is the provision of a frame which is sufficiently flexible to allow the same to conform to the surface of the glass, thereby reducing the liability of the breakage of the same in positioning it in the window opening.

A still further object of the invention is the provision of a frame which is of simple construction, inexpensive to manufacture and which is thoroughly reliable and efficient in its purpose.

With these and other objects in view, the invention resides in the novel construction, combination and arrangement of parts fully described and set forth in the following description and claims and illustrated in the accompanying drawings, in which,

Figure 1, designates a front elevation of the device in applied position.

Fig. 2, is a sectional view on the line 2—2, of Fig. 1.

Fig. 3, is a fragmentary detailed perspective view of the frame showing the means for securing the sections in clamped relation.

Fig. 4, is a sectional view of a slightly modified form of the invention, and

Fig. 5, is a perspective view of the securing means therefor.

Fig. 6, is a sectional view of a still further modified form of the invention.

Referring to the drawings, like characters designate similar parts throughout the several views of the drawing. A represents a portion of the vehicle top which is usually constructed of cloth composition and B the glass or other material of a transparent nature which is adapted to fill the window opening in the top. C designates the frame which comprises the sections 10 and 11, the former being provided with an inturned flange 12, and the latter with a similar flange 13. The section 11 has arranged therein a leaf spring 14, which is preferably soldered at one extremity to the inner surface of the same. Adjacent the free end, the spring is bent at 15, to form a catch for engagement with the flange 12. The remaining extremity 16, of the spring forms an inclined surface which is adapted to be engaged by the flange 12, when bringing the sections into clamping position, whereby the flange 12, will be allowed to pass over and engage behind the portion 15, as will be readily understood. The flanges 12 and 13, serve as jaws for clamping the cloth A, therebetween. The remaining edges 17 of the sections are adapted to grip the glass B, therebetween as will be seen clearly in Fig. 2. Any number of springs may be employed to accomplish the clamping action described and after the frame and glass have once been positioned in place within the window opening, it is immaterial whether the soldering which secures the spring to the frame loosens, as the arrangement and form of the spring will cause the same to remain in place. In applying the frame and glass to the window opening one section of the frame is positioned with relation to the window, the glass is properly placed in position and the other section is snapped into clamping position. It will thus be seen that a very short space of time is required within which to accomplish the applying of the glass and frame to the opening. It will be further noted that the frame is of relatively flexible material which will allow the same to readily conform to the surface of the glass, thus minimizing the liability of breakage of the same as is the case in frames of an inflexible character.

In the modified form shown in Figs. 4 and 5, the sections 10^a and 11^a are preferably provided with two inturned flanges 12^a and 13^a, which form two sets of clamping jaws between which the cloth A, and the glass B,

are adapted to be clamped. The spring 14^a, at its point of connection with the sections 11^a, is bent inwardly as at 18, and upwardly as at 19. The portion 19, serves as a limiting means which aids in the positioning of the glass with relation to the frame. The portion 18, is adapted to underlie one of the flanges 13^a.

In the modified form illustrated in Fig. 6 of the drawings, the clamping section 10^b is provided with the inwardly extending flanges 12^b and 13^b, the former being provided with a downturned extremity 14^b. The section 11^b is provided with inturned flanges 15^b and 16^b, the former being provided with the upturned extremity 17^b, which serves as a limiting means for the glass panel and aids in positioning the same when applying the frame. The downturned extremity 14^b of the flange 12^b co-acts with the flange 16^b, to securely retain the frame in place on the cloth. It will be noted that the construction of the two sections 10^b and 11^b, are complementary. In this form a suitable spring 18^b, is provided which is of substantially the same formation as the spring 14, shown in Fig. 2, of the drawings.

While I have shown and described several simple forms of carrying my invention into practice, I do not care to be limited to the exact details of construction therein exhibited, but desire to receive the right to make such changes and alterations as fall within the scope of the appended claims.

35 What I claim as new is:

1. A window frame comprising a pair of hollow separable sections, having surfaces at one side mutually arranged to receive the edge of a transparent medium therebetween, flanges formed on the sections at the opposite side and adapted to receive therebetween, the edge of a curtain body with which the frame is arranged to be associated, the said flanges arranged side by side 45 in clamping relation with each other, and means for securing the sections together, said means including a free end adapted to engage the flange of one section for moving the same into co-acting relation to the flange 50 of the other section, as and for the purpose specified.

2. A window frame comprising a pair of separable frame sections arranged one against the other and adapted at one side to receive a panel therebetween, inwardly projecting clamping portions formed on the sections at the opposite side of the frame and disposed in such relation so as to receive

therebetween the edge of the object with which the frame is arranged to be connected, 60 and a spring carried by one section and provided with a free end arranged in overlapping relation with one of said clamping portions and adapted to move the same into clamping contact with the corresponding 65 portion of the other section.

3. A window frame comprising a plurality of hollow sections arranged one against the other, the said sections at one side, being adapted to receive a panel therebetween, and flanges on said sections at the opposite side thereof, and a plurality of springs carried by one of said sections for co-acting engagement with said flanges to hold said sections against each other. 75

4. A window frame comprising a plurality of frame sections, flanges on said sections at one side, flanges on said sections at the opposite side thereof, the first flanges being adapted to receive the edge of a panel therebetween, the second flanges being adapted to receive the edge of a cloth therebetween in surrounding relation to said panel, and a spring carried by one of said sections and provided with an extension lying across said panel receiving flanges and forming a rest for the edge of the panel, and a free terminal on said spring for moving the cloth receiving flanges into clamping engagement with the cloth and for securing the sections 85 of said frame together. 90

5. A window frame comprising a pair of hollow clamping sections, co-acting inturned flanges formed on said sections, to provide jaws for engagement with the object to be clamped, the said sections at the inner side of the frame arranged to receive the edge of a transparent medium therein, and means located within one of said sections adapted to co-act with the flange of the first mentioned section to move the same relatively of the flange of the other section and secure both sections in clamped relation. 95

6. A window frame comprising a plurality of relatively separable sections adapted at one side to receive the edge of a transparent medium therebetween, flanges on the respective sections at the opposite sides thereof between which the object with which the frame is arranged for connection is adapted to be received, and a spring extending over the joint between the sections and co-acting with the flanges to hold the sections in clamped relation. 105 110

In testimony whereof I affix my signature. 115
HENRY P. DAVIS.
